VALVE ACTUATING MECHANISM

Oscar H. Banker, Chicago, Ill.

Application July 24, 1936, Serial No. 92,302

7 Claims. (Cl. 123—90)

The invention relates generally to a valve actuating mechanism for an internal combustion engine and more particularly to the valve lifter of the actuating mechanism.

5 A general object of the invention is to provide a valve actuating mechanism of new and improved construction rendering the mechanism extremely quiet under all operating conditions, economical to manufacture, efficient, durable, and 10 easy to install either initially or as a replacement for noisy, worn or obsolete mechanism.

A more particular object is to provide a valve actuating mechanism of new and improved construction in which metal to metal contact blows 15 are eliminated, thereby avoiding the noise and the periodic vibration incident to such blows.

Another object is to provide a valve actuating mechanism having a two part valve lifter, one part being maintained in constant engagement 20 with the valve stem and the other part being maintained in constant engagement with the valve actuating cam and the parts having a new and improved cushioned engagement of large area, assuring long life of the cushioning material and ready separation of the engagement so 25 that the parts will be maintained respectively in engagement with the valve stem and the cam.

Other objects and advantages will become apparent from the following detailed description. 30 taken in connection with the accompanying drawing, in which:

Fig. 1 is a view, partially in section, of a valve actuating mechanism for an internal combustion engine embodying the features of the invention.

35 Fig. 2 is a diametrical section of the valve actuating mechanism shown in Fig. 1.

Fig. 3 is a diametrical sectional view of a modified form of the valve lifter of the valve actuating mechanism.

40 Fig. 4 is a fragmentary diametrical sectional view of still another modified form of valve lifter.

While the invention is disclosed in the drawing and will hereinafter be described as embodied in 45 three forms or modifications, it is not intended that the invention be limited to the specific embodiments disclosed, but it is intended to cover all modifications and alternative constructions falling within the spirit and scope of the invention as defined by the appended claims.

50 Referring to the drawing, particularly Fig. 1, 10 represents the cylinder block of an internal combustion engine and 11 represents a valve having a valve head 12 controlling a port opening 55 into a cylinder of the engine. The valve is

mounted in the usual manner with its stem 13 projecting slidably through a sleeve bushing 14 secured in the cylinder block 10. At the end remote from the valve head, the valve stem carries a washer 15 between which and the cylinder block 5 10 a compression spring 16 is interposed to urge the valve toward seated position. The valve is opened against the action of the spring 16 at proper intervals by means of a cam 17 formed on a cam shaft 18 and acting through a valve 10 lifter generally designated 19. The valve lifter is guided for longitudinal reciprocatory movement in a bore 20 formed in a portion of the cylinder block 10.

15 Herein the valve lifter is of unique construction designed to silence the operation of the valve mechanism. Generally, the valve lifter comprises a first part generally designated 21 maintained in contact with the cam shaft 18, a second part generally designated 22 maintained in contact with the valve stem and a cushioning means interposed between the parts so as to avoid metal to metal impact blows during the operation of the engine. The parts have a joint movement to unseat the valve and a slight movement relative to one another in order at all times to maintain the parts in contact with the cam shaft and the valve stem respectively and to provide the clearance necessary to take care 20 of expansion of the valve mechanism caused by 25 changes in engine temperature.

30 In the form of the valve lifter shown in Fig. 2 the first or cam mechanism operated part 21 comprises a cylindrical main body portion 25 having a longitudinal bore 26 opening through 35 the end remote from the cam shaft 18 and a reduced neck 27 at the same end. Mounted on the neck end of the main body portion 25 is a cup-shaped member 28 having a hub portion 29 fitting over the neck 27 and by means of which the cup-shaped member is secured by a press fit to the main body portion 25. Disposed within the cup-shaped member 28 is a metallic washer 30 welded thereto as indicated at 31 and having a central aperture coinciding with the bore 26 of the main body portion. For a purpose which will become apparent hereinafter, the cup-shaped member 28 is of substantial diameter, larger even than the diameter of the main body portion 25 and several times larger than the diameter of 40 45 50 55 the valve stem 13.

The second or valve mechanism operating part 22 of the valve lifter consists of a disk-like cap 34 having a cylindrical guide portion or plunger 33 slidable in the bore 26. The cap 34 is pref- 55

erably slightly less in diameter than the inner diameter of the cup-shaped member 28, and has a boss 35 extending axially therefrom for engagement with the valve stem. At the inner 5 end the plunger is reduced at 36 to provide a seat for one end a compression spring 37 disposed in the bore 26 between the plunger and the main body portion 25. This spring tends to separate the two parts of the device and thus 10 maintains the main body portion or cam shaft part in contact with the cam shaft 18 and the cap or valve stem part in contact with the valve stem 13. Spring 37, of course, is weaker than spring 16.

15 Interposed between the parts 22 and 21 and herein in effect forming a portion of the cam operated part 21 is a cushioning means of non-metallic material mounted in the member 28 and arranged to engage the cap 34 and thereby limit 20 the approaching movement of the parts 21 and 22. This cushioning means takes the form of an annular washer 38 of a composition which is 25 resilient and slightly yieldable but substantially incompressible volumetrically so that in order to yield in one direction or be compressed in part it must have space to expand in another direction or in another part. The resilient qualities are similar to those of rubber, but preferably the composition also does not deteriorate when 30 exposed to heat and oil, a suitable composition being the commercial product known as "Durene," which is a product made from coal having some of the characteristics of rubber.

As illustrated in Fig. 2 the washer 38 fits snugly 35 in the cup-shaped member 28 so that it cannot expand radially, and the adjacent sides of the cap 34 and the washer 38 are formed so as to provide space into which a portion of the composition of the washer may expand when 40 another portion of it is compressed longitudinally. Preferably, one of the parts is beveled or otherwise formed relatively to the other so that there will be a gradually increasing area of contact between the parts as the valve lifter is actuated to unseat the valve. Herein the cap 34 is beveled and the adjacent surface of the washer 38 is flat. Such gradually increasing contact results from the relative movement of the parts 45 21 and 22 from the upward distortion of the outer portion of the washer 38 under such movement. This assures that the engagement of the parts will be gradual and not a sudden impact, and nevertheless the extent of the movement of the parts toward each other is limited definitely 50 by the space into which a portion of the washer may expand. Moreover, the large contact area 55 of the washer 38 (it being many times that of the valve stem 13), assures that the pressure per unit area is low enough so that the washer 60 will have a long life. The beveled underneath surface of the cap also assures that the cap and the washer 38 will again separate as the valve is returned to seated position and will not be held together by any suction-cup action.

65 Positioned between the annular washer 38 and the bottom of the cup-shaped member 28 are a plurality of shims 39 which preferably are of different thickness so that by the employment of different combinations the desired clearance 70 in the valve mechanism may be obtained. This clearance is of an order of a few thousandths of an inch when the engine is cold resulting in a slight space between the cap 34 and washer 38 as shown in Fig. 2. As the engine warms up, however, 75 this space may disappear and the under-

portion of the cap 34 always bears upon the washer 38. Under such a condition, the resilient and yieldable character of the washer 38 still assures proper seating of valve 11 by the spring 16.

It will be apparent from the foregoing that the spring 37 maintains the main body portion 25 and the cap 34 respectively in contact with the cam 17 and the valve stem 13 and that the clearance provided to compensate for expansion of the valve mechanism appears between the parts of the valve lifter and not between the valve lifter and the valve stem. Thus, with the parts of the valve lifter constantly in engagement with the cam and the valve stem respectively, there are no metal to metal impacts at those points. The entire impact resulting from the rapid movement imparted to the valve lifter by the cam 17 is taken between the washer 38 and the cap 34, and thus is cushioned and silenced both because of the resilient character of the washer 38 and because of the beveled underneath surface of the cap 34 causing a gradually increased area of contact between the washer and the cap.

25 Fig. 3 shows a modified form of valve lifter in which a cam operated part 21' is formed partly by a cylindrical member 25' having a bore 26' therein opening through the end remote from the cam shaft. The second part 22' is formed by a cap 41 having a diameter substantially equal to the diameter of the bore 26' and a stem 42 of a substantially reduced diameter. The cap 41 is normally received partially within the cylindrical member 25' and in order to facilitate 30 relative movement between the cap and the cylindrical member 25', the latter is cut away at 43 so as to provide sufficient clearance so that the cap will not stick. The cushioning means 35 interposed between the two parts of the valve 40 lifter herein comprises a plurality of annular washers 38' of a resilient but substantially incompressible composition not affected by heat and oil, such as the commercial product known as "Durene." These washers have an outer 45 diameter substantially equal to the diameter of the bore 26' and an inner diameter substantially equal to the diameter of the stem 42.

Interposed between the washers 38' are a plurality of shims 39' having an outer diameter 50 which is less than the diameter of the bore 26'. As a result, a plurality of spaces 44 are formed into which the composition of the washers 38' 55 may expand when the washers are placed under compression during the unseating of the valve by the valve lifter or upon expansion of the valve mechanism. The total distortion of the washers 38' into the spaces 44 is comparable to the clearance to be maintained in the valve mechanism when cold. In this form the washers 38' serve 60 the dual function of separating the main body portion 25' and the cap 41 to maintain them respectively in contact with the cam shaft and with the valve stem and of providing the cushioning means for eliminating the metal to metal 65 impact blow. When the parts are in their separated position as shown in Fig. 3, the plunger stem 42 is spaced from the bottom of the cylindrical member 25' a distance slightly greater than the distance which the washers 38' normally 70 permit the plunger to move. This construction thus provides a positive safety limit to the compression of the washers 38' in case of deterioration which may not be exceeded during the unseating of the valve by the valve lifter.

Fig. 4 shows a form of valve lifter embodying the features of this invention which is particularly well adapted for substitution in existing valve actuating mechanism for it entails the replacement of a smaller part of the mechanism than does the form shown in Figs. 1 to 3. To that end a cup-shaped member 28" is formed with an axial tubular extension 45 which is received within the threaded end of a standard valve lifter body portion 25". A washer 46 may be inserted above the body 25" as shown to strengthen the bottom of the cup-shaped member. The cup-shaped member 28" thus may readily replace the adjusting screw and lock nut normally threaded into the body portion 25" to provide for adjustment of the clearance normally maintained in the valve actuating mechanism.

The valve stem part of the valve lifter in the form shown in Fig. 4 is composed of a cap 34" and a materially fore-shortened plunger 33", the cap fitting partially within the cup-shaped member to be guided thereby. Projecting axially beyond the cap 34" is a valve stem engaging boss 35" while the inner face of the plunger is formed with a recess 36". This recess forms a seat for one end of a compression spring 37", the other end of which abuts the bottom of the tubular extension 45 to separate the parts of the valve lifter in the manner of and for the same purpose as the spring 37 in the form shown in Fig. 2. Interposed between the cap 34" and the cup-shaped member 28" to cushion the impact of the parts is an annular washer 38" like that shown in Fig. 2. Shims 39" are preferably interposed between the washer 38" and the bottom of the cup-shaped member 28" to enable the clearance to be adjusted. The underneath surface of the cap 34" is again beveled to ease the impact and to insure separation of the cap from the washer 38".

It is believed readily apparent that the invention provides a simple and inexpensive means for insuring quiet operation of the valve actuating mechanism, and furthermore that it may be embodied in forms which fit into existing valve actuating mechanism merely by the removal of portions thereof. Thus in the forms illustrated in Figs. 2 and 4, the invention is adapted for installation in existing valve mechanism by removing the adjusting screw and nut portions thereof and affixing the invention to the standard valve lifter parts 25 and 25". In the form illustrated in Fig. 3, it is contemplated that the existing valve lifter part will be completely replaced or that this form may be embodied in valve mechanisms when originally designed. It is, of course, contemplated that various features of the invention may be embodied in original valve mechanism designed to obtain even further simplification. For example, the valve stem part 22 might readily be formed integrally with the valve stem 13.

By maintaining the valve stem and cam shaft parts of the present invention in continual contact with the valve stem and cam shaft respectively, and providing a cushioning engagement between the parts, there will be no impact blows between two metal parts during the operation of the mechanism as is the case in the present day valve mechanism wherein clearance is provided between the upper end of the valve lifter and the valve stem.

By making the washers 38 with a contact area many times that of the lower end of the valve stem 13, the pressure per unit area on the com-

position washer is low enough so that the washer will have a long life. In the form illustrated in Fig. 3, means is provided for maintaining a positive safety limit to the compression of the washer 38", but in the forms illustrated in Figs. 2 and 4 the washers 38 and 38" are so thin that even if there is excessive deterioration the valve mechanism will still function to open the valve.

The invention provides a particularly simple and practical device for adaptation in new engine designs and facilitates the placing of such engines in motor cars since it is not necessary to provide accessibility for valve adjustment. Since there are no screw devices used for adjusting the valves, shims serving this purpose, the adjustment will be more permanent and will eliminate the tight and loose valves nowadays caused by vibration changes of the screw device adjustments. Heretofore shims were not practical because of the small contact area of the valve lifter parts limiting the size of the shims so that the pressures encountered during operation would crush and destroy them, but the invention herein disclosed, which increases the area to many times that of the valve stem, makes it possible to use thin metal shims for adjustment purposes when the valve mechanisms are initially installed.

Although the invention is herein illustrated and described in connection with an L-head type of engine, it is to be understood that the invention in its various forms is equally suitable for use in connection with "overhead valve" engines wherein the valve operating member 22 would engage the usual push rods of the valve mechanisms of such engines. Since "overhead valve" engines are well known in the art, it is not thought necessary to illustrate the valve actuating mechanism thereof herein. In "overhead valve" engines all adjustment screws and lock nuts usually furnished on the rocker arms will be eliminated just as adjusting screws and lock nuts are eliminated in the valve mechanism illustrated.

I claim as my invention:

1. In an internal combustion engine having a cylinder block, a cylinder, a port opening into the cylinder and a valve controlling the port, valve actuating mechanism comprising a cam shaft and a valve lifter interposed between the shaft and the valve comprising a tubular member adapted to be operated by said cam shaft and guided for longitudinal reciprocatory movement, said member having an axial bore opening through the end remote from the cam shaft, a cup-shaped member having a central aperture equal in diameter to the diameter of the bore in said tubular member and an annular longitudinal flange intermediate the aperture and the periphery of the cup forming a hub for mounting the member on said tubular member, a washer of heat and oil resistant, resilient composition in said cup-shaped member and a plurality of shims interposed between the bottom of said cup-shaped member and said washer to determine the position of the washer in the member, a valve operating member having a cylindrical portion slidable in the bore in said tubular member and a disk-like cap portion adapted to engage the washer to be limited thereby in its movement relative to the tubular member, said disk-like portion being beveled on its washer engaging face, and a compression spring disposed in the bore with one end abutting the end of the tubular member and the other end abutting the

valve operating member to maintain the same respectively in engagement with the cam shaft and with the valve.

2. In a valve lifter for valve actuating mechanism, a first part having a cup-shaped member at one end thereof, a second part mounted for joint movement with said first part and for limited movement relative thereto having an annular radial flange, the adjacent surface of which 10 has the shape of the frustum of a cone having its apex toward said first part, and an annular washer of resilient material mounted in said cup-shaped portion and having a flat surface adapted to contact the frusto-conical surface of the 15 flange progressively as the parts are moved toward each other.

3. A silencer for valve actuating mechanism comprising, in combination, a first member having a tubular portion insertable in the adjusting screw hole of a valve lifter and an enlarged annular flange extending outwardly from the upper end of said tubular portion and an upright annular wall extending peripherally of said flange to form a cup-shaped end, a plurality of 25 shims positioned in said end, a member of synthetic resilient material positioned against said shims and within said wall, a second member comprising a disk portion having its underneath surface beveled and in engagement with said 30 member, an abutment on its other surface for engagement with a valve stem, and a coil spring positioned within said tubular portion of said first member and engaging the adjacent side of said second member for maintaining said members 35 in contact with said valve lifter and valve stem respectively.

4. In a valve actuating mechanism for internal combustion engines, a valve lifter adapted to be interposed between the cam shaft of the engine and the valve to be actuated comprising, a first part adapted to be operated by the cam shaft having a depression at the top thereof, a second part adapted to operate the valve comprising a radially extending annular portion having 45 a face at the side thereof opposite the first part and an axial central portion extending toward said first part, and an annular resilient member supported in the depression comprising material yieldable under pressure having a face 50 opposite the face on said second part and a central aperture adapted to receive said axial central portion so as to serve as a cushioned guide for said axial portion, said faces being separated from one another by distances increasing outwardly from the central portion to provide upon 55 the yielding of said member an area of contact variable progressively in quantity during operation of the device.

5. A valve silencing device for insertion between a valve cam and valve stem of an internal

combustion engine comprising, in combination, a tubular member in contact with the cam having a cup-shaped upper end, an annular resilient member of substantial thickness confined radially entirely within said cup-shaped end, a plunger 5 having a central portion reduced in cross section to form a stem extending within the central aperture of the resilient member and laterally cushioned thereby, a substantial elastic means in the tubular member in contact with the plunger adjacent the reduced end for urging said plunger in a longitudinal direction, said plunger having a flanged central portion provided with a face adjacent the resilient member of a frusto-conical shape with the apex thereof in initial contact with said resilient member adjacent the central aperture and adapted to provide an increase in contact area therewith in a geometric ratio as the pressure on said device increases, and an upward extending portion on said plunger in 20 contact with the valve stem.

6. A valve actuating device for insertion between the cam shaft and the valve of an internal combustion engine comprising a first member adapted to be operated by the cam shaft and guided for longitudinal reciprocatory movement, said member having an axial bore opening through the end remote from the cam shaft, a cup-shaped member mounted on said last mentioned end of said first member, an annular washer of heat and oil resistant resilient composition in said cup-shaped member, and a plurality of shims interposed between the bottom of said cup-shaped member and said washer to determine the position of the washer in the cup-shaped member, a valve operating member having a cylindrical portion projecting into the aperture in said annular washer to be guided thereby and a disk-like cap portion to engage the washer to be limited thereby in its movement relative to the cup-shaped member, said disk-like portion being beveled on its washer engaging face, and a compression spring disposed intermediate said first member and said valve operating member to maintain the same respectively in engagement with the cam shaft and with the valve stem.

7. A silencer for valve actuating mechanism comprising, in combination, a first member having a cup-shaped end, a plurality of shims positioned in said end, a member of synthetic resilient material positioned against said shims and within the cup-shaped end, a second member comprising a disk portion having its underneath surface beveled and in engagement with said resilient member and an abutment on its other surface for engagement with a valve stem, and a coil spring positioned intermediate said first member and the adjacent side of said second member for separating said members.

OSCAR H. BANKER.
